CLAIM

The ornamental design for a gaming machine, as shown and described.

DESCRIPTION

FIG. 1 is a front top right perspective view of a gaming machine showing our new design;

FIG. 2 is a front bottom left view thereof;

FIG. 3 is a front view thereof;

FIG. 4 is a left side view thereof; and,

FIG. 5 is a right side view thereof.

The broken lines immediately adjacent to a shaded area define the bounds of the claimed design and form no part thereof. The broken lines depicting the remainder of the gaming machine show features that form no part of the claimed design. The oblique line shading shows that the surface is a transparent, translucent, highly polished or reflective surface.
